WOMAN'S STOCKING

Aaron Burleson, Burlington, N.C., assignor to Burlington Industries, Inc., Greensboro, N.C., a corporation of Delaware

Filed Oct. 22, 1964, Ser. No. 82,284

Term of patent 14 years

(Cl. D47—7)

Fig. 1.

Fig. 2.

Fig. 3.

FIGURE 1 is a side elevational view of a stocking showing my new design;

FIGURE 2 is an enlarged side elevational view of the toe pocket of the stocking showing the appearance of the same in a flattened but essentially untensioned state; and

FIGURE 3 is an enlarged side elevational view of the heel pocket of the stocking showing the appearance of the same in a flattened but essentially untensioned state.

The dominant feature of the stocking shown herein resides in the toe pocket which consists in a series of ribbed bands wherein the ribs of each band are angularly disposed in relation to the ribs of each adjacent band so as to present a zigzag or herringbone effect of ribs, said bands terminating in an undulating seam and being obliquely disposed in relationship thereto so as to present a broken chevron effect, said toe pocket having a band of uniform stitching encircling the stocking between the

toe pocket and the foot portion thereof; and a heel pocket which consists of a series of ribbed bands wherein the ribs of each band are angularly disposed in relation to the ribs of each adjacent band so as to present a zigzag or herringbone effect of ribs, essentially as shown.

I claim:

The ornamental design for a woman's stocking, substantially as shown and described.
